EXTRACTION OF DYEWOOD

Raymond L. Drew, Arlington, N. J., assignor to
 American Dyewood Company, New York, N. Y.,
 a corporation of Pennsylvania

Application September 30, 1941, Serial No. 412,963

15 Claims. (Cl. 260—333)

This invention relates to the extraction of dyewoods and particularly to the preparation of pure extracts free from wood sugars, tanning materials, and other inert substances. While the invention will be described more particularly in connection with the treatment of logwood, it may be utilized in preparing similar extracts of other dyewoods such as hypernic, fustic and osage.

The extraction of dyewoods is a relatively old art which has been conducted on a commercial scale for many years. The procedure heretofore followed is extremely simple. The dyewood is chipped and digested with water and steam until the water soluble content of the chips has been extracted. The chips are discarded and the extract, containing wood sugars, tanning materials and other inert substances soluble in water are then concentrated by evaporation to afford a material of the consistency of thin molasses. This product, contaminated with the water soluble constituents of the wood, has been supplied to the trade and utilized without further purification for the purposes for which dyewood extracts are commonly used.

The coloring material in logwood is haematoxylin. In the form in which the heavy extract has been supplied to the trade heretofore, the value of the haematoxylin as a coloring agent has been reduced somewhat by the presence of the impurities mentioned. However, there has been heretofore no practicable commercial method which permitted separation of the contaminating materials in an economical manner and hence pure haematoxylin has not been available except in small amounts produced by elaborate laboratory methods.

It is the object of the present invention to provide a simple and effective commercial method of recovering coloring materials from dyewoods free from contamination with wood sugars, tanning materials and other inert substances.

Another object of the invention is the provision of an economical method of preparing substantially pure haematoxylin from logwood.

Other objects and advantages of the invention will be apparent as it is better understood by reference to the following specification and the accompanying drawing, which diagrammatically illustrates, in the form of a flow sheet, an apparatus and procedure adapted for the accomplishment of the purpose of the invention. Details of the apparatus familiar to those skilled in the art have been omitted for the purpose of clarity.

I have discovered that haematoxylin, in the presence of wood sugars and the like, has a pref-

erential solubility in certain organic solvents, and that it may be separated from water solutions by treatment with such solvents. I have further discovered that in the absence of wood sugars and the like, haematoxylin exhibits a preferential solubility in water so that it may be separated from the organic solvent by treatment with water. These discoveries afford the basis for a simple and effective procedure for the recovery of substantially pure haematoxylin from the heavy extract produced by digestion of the dyewood chips with water. Thus, in the practice of the invention, I carry out the usual digestion of the chips in water with steam, and separate the extract from the chips. The extract is then concentrated by evaporation in the usual manner. The heavy extract is then agitated with a suitable solvent. Such a solvent should be substantially immiscible with water and a solvent which will 5 separate the haematoxylin from the wood sugars, tanning materials and the like, which are insoluble in the solvent. Normal butyl alcohol has in practice proved to be the most satisfactory solvent. Other solvents such as methyl ethyl ketone, 10 furfural, tertiary amyl alcohol and secondary butyl alcohol are among other available solvents. There are, of course, many commercial organic solvents, and any such solvent having the desired properties could be employed. Hence the list of 15 solvents herein mentioned is not exhaustive.

Following the treatment of the heavy extract with the organic solvent, the latter, containing the haematoxylin, can be separated readily, by settling or otherwise, in a suitable separator. 20 The water layer containing the wood sugars, tanning materials and the like, which are insoluble in the solvent, is discarded. Normal butyl alcohol has in practice proved to be the most satisfactory solvent. Other solvents such as methyl ethyl ketone, furfural, tertiary amyl alcohol and secondary butyl alcohol are among other available solvents. There are, of course, many commercial organic solvents, and any such solvent having the desired properties could be employed. Hence the list of 25 solvents herein mentioned is not exhaustive.

Following the treatment of the heavy extract with the organic solvent, the latter, containing the haematoxylin, can be separated readily, by settling or otherwise, in a suitable separator. 30 The water layer containing the wood sugars, tanning materials and other impurities, is discarded. The layer containing the haematoxylin is withdrawn and agitated with water which, as previously indicated, again takes up the haematoxylin which is preferentially soluble in the water in the absence of the impurities which have been removed. Following agitation, the liquor may be again separated by gravity or otherwise. The organic solvent, now substantially free from 35 haematoxylin, is sent to a solvent recovery still where the solvent is recovered for further use, the residue being discarded. The water layer containing the haematoxylin is subjected to evaporation to produce a heavy extract of haematoxylin which is free from the impurities originally present. This liquor may be utilized for the purposes for which the impure heavy extract has been previously employed. Obviously, because of the 40 elimination of impurities, it affords a more desirable and satisfactory product, in which the color

is stronger in addition to its other advantages. By a series of recrystallizations in the ordinary manner, pure crystalline haematoxylin can be recovered readily from the purified heavy extract. For some specialized purposes, such pure crystalline material has certain commercial advantages.

Since the organic solvent may to some slight extent be miscible with or soluble in the water, the vapor from the evaporator in the final stage is preferably delivered to a solvent recovery still from which any remnant of the solvent may be recovered and delivered to the solvent storage tank for further use. The residue, consisting of water, is discharged.

Except in the initial stage of extracting the chips, the temperature at which the operation is conducted may be varied widely, so long as the boiling point of the solvent is not exceeded. The operations may be conducted successfully at ordinary room temperature or even at considerably lower temperatures. The temperatures may be raised above room temperature to accelerate the operation if such acceleration is desirable. The time of contact between the organic solvent and the heavy extract, and the time of treatment of the organic solvent with water, are likewise subject to wide variation. The time for each of these operations can be controlled readily to obtain the desired result.

In order that the invention may be more clearly understood, reference is made to the drawing, in which 5 indicates the chip digester to which water and steam are introduced through pipes indicated at 6 and 7. The spent chips are discharged after suitable treatment. The extraction of the chips consumes normally about twenty-four hours, or more or less time may be required, depending upon the character of the chips treated. The operation is in all respects comparable with the well known digestion treatment which has been practised for many years.

In accordance with the invention, the liquor from the digester 5 is conveyed through a pipe 8 to an evaporator 9. Any suitable type of evaporator may be used. The heavy extract is delivered through a pipe 10 to an extractor 11 having an agitator 12 driven by a motor 13 or from any suitable source of power. The solvent, for example normal butyl alcohol, is supplied from a storage tank 14 through a pipe 15. Agitation of the heavy extract with the organic solvent results, as hereinbefore stated, in the selective solution of the haematoxylin, leaving the wood sugars, tanning material, etc., in the water.

The water and organic solvent pass through a pipe 16 to a separator 17. Any suitable separator may be employed. When separation is effected, the water is discharged through a pipe 18 and the organic solvent carrying the haematoxylin passes through a pipe 19 into a second extractor 20. This likewise is provided with an agitator 21 driven by a motor 22 or any other suitable source of power. Water is introduced through a pipe 23, and agitation is continued until the haematoxylin has again been dissolved in the water.

The mixture of organic solvent and water is then conveyed through a pipe 24 to a separator 25 of any suitable form. The solvent layer from the separator, which is now freed from haematoxylin, is discharged through a pipe 26 to a solvent recovery still 27 from which the solvent is withdrawn through a pipe 28. The solvent may be returned to the storage tank 14. The 75

residue from the still is discharged through a pipe 29.

The water layer from the separator 25 carrying the haematoxylin passes through a pipe 30 into an evaporator 31. Any suitable type of evaporator may be used. The purified heavy extract is withdrawn through the pipe 32. This extract, as hereinbefore indicated, is free from wood sugars, tanning materials and the like, and constitutes a superior product adapted for the uses of haematoxylin solutions. Crystalline haematoxylin can be recovered therefrom by crystallization, and if purer forms are required, recrystallization will result in the separation of any minute proportions of impurities which may be present.

In order that none of the solvent may be lost, the evaporate is conducted through a pipe 32' to a solvent recovery still 33 in which the solvent is withdrawn through a pipe 34. The solvent may be returned to the storage tank 14. The residue escapes through a pipe 35.

As hereinbefore indicated, the temperature and time of extraction are not critical in the foregoing operations. Except for the use of steam in the initial digestion of the chips and the application of heat in the evaporator 31, and the recovery stills 27 and 33, the various operations may be conducted satisfactorily at room or higher or lower temperatures as may be desired. The invention resides, therefore, in the practical application of the preferential solubilities of the haematoxylin in organic solvents and in water according to the particular conditions with respect to the presence or absence of wood sugars and other impurities in the extract.

Various changes may be made in the procedure and particularly in the details of the apparatus and the operation without departing from the invention or sacrificing any of the advantages thereof.

I claim:

1. The steps in the method of extracting dyewood which comprise treating a crude water extract of the dyewood with an organic solvent substantially immiscible with water and having a preferential solvent effect on the coloring constituent of the dyewood, separating the organic solvent, and then extracting the solvent with water to recover the coloring constituent in water solution.

2. The steps in the method of extracting dyewood which comprise treating a crude water extract of the dyewood with an organic solvent from the class including normal and secondary butyl alcohols, methyl ethyl ketone, furfural and tertiary amyl alcohol, separating the organic solvent and then extracting the solvent with water to recover the solvent and the coloring constituent of the dyewood in water solution.

3. The method of separating the coloring constituent of dyewood from impurities present in a crude water extract thereof which comprises treating the crude water extract with an organic solvent substantially immiscible with water and having a preferential solvent effect on the coloring constituent, separating and discarding the water solution, retaining the impurities and extracting the organic solvent with water to recover the solvent and the coloring constituent of the dyewood in water solution.

4. The method of separating the coloring constituent of dyewood from impurities present in a crude water extract thereof which comprises treating the crude water extract with an organic

solvent substantially immiscible with water and having a preferential solvent effect on the coloring constituent, separating and discarding the water solution, retaining the impurities, extracting the organic solvent with water to recover the solvent and the coloring constituent of the dyewood in water solution, and recrystallizing the water solution to separate pure crystals of the coloring constituent.

5. The method of separating the coloring constituent of dyewood from impurities present in a crude water extract thereof which comprises treating the crude water extract with an organic solvent from the class including normal and secondary butyl alcohols, methyl ethyl ketone, furfural and tertiary amyl alcohol, separating and discarding the water solution, retaining the impurities and extracting the organic solvent with water to recover the solvent and the coloring constituent of the dyewood in water solution.

6. The method of separating the coloring constituent of dyewood from impurities present in a crude water extract thereof which comprises treating the crude water extract with an organic solvent from the class including normal and secondary butyl alcohols, methyl ethyl ketone, furfural and tertiary amyl alcohol, separating and discarding the water solution, retaining the impurities, extracting the organic solvent with water to recover the solvent and the coloring constituent of the dyewood in water solution, and recrystallizing the water solution to separate pure crystals of the coloring constituent.

7. The method of eliminating impurities from crude dyewood water extract which comprises treating the crude extract with an organic solvent substantially immiscible with water and selectively effective to dissolve the coloring constituent of the dyewood, discharging the water carrying the impurities, extracting the organic solvent with water to separate the coloring constituent and recovering the organic solvent for further use.

8. The method of eliminating impurities from crude dyewood water extract which comprises treating the crude extract with an organic solvent from the class including normal and secondary butyl alcohols, methyl ethyl ketone, furfural and tertiary amyl alcohol, discharging the water carrying the impurities, extracting the organic solvent with water to separate the coloring constituent and recovering the organic solvent for further use.

9. The method of eliminating impurities from crude dyewood water extract which comprises treating the crude extract with an organic solvent substantially immiscible with water and selectively effective to dissolve the coloring constituent of the dyewood, discharging the water carrying the impurities, extracting the organic solvent with water to separate the coloring constituent, recovering the organic solvent for further use, and recrystallizing the water solution

to separate pure crystals of the coloring constituent.

10. The method of separating substantially pure haematoxylin from crude haematoxylin water extract which comprises treating the crude extract with a water immiscible organic solvent for haematoxylin, separating the water containing the impurities in solution and extracting the organic solvent with water to redissolve the haematoxylin in water.

11. The method of separating substantially pure haematoxylin from crude haematoxylin water extract which comprises treating the crude extract with an organic solvent for haematoxylin from the class including normal and secondary butyl alcohols, methyl ethyl ketone, furfural and tertiary amyl alcohol, separating the water containing the impurities in solution and extracting the organic solvent with water to redissolve the haematoxylin in water.

12. The method of separating substantially pure haematoxylin from crude haematoxylin water extract which comprises treating the crude extract with a water immiscible organic solvent for haematoxylin, separating the water containing the impurities in solution, extracting the organic solvent with water to redissolve the haematoxylin in water, and recrystallizing the water solution to separate pure crystals of the coloring constituent.

13. The method of separating substantially pure haematoxylin from crude haematoxylin water extract which comprises treating the crude extract with an organic solvent for haematoxylin from the class including normal and secondary butyl alcohols, methyl ethyl ketone, furfural and tertiary amyl alcohol, separating the water containing the impurities in solution, extracting the organic solvent with water to redissolve the haematoxylin in water, and recrystallizing the water solution to separate pure crystals of the coloring constituent.

14. The method of separating substantially pure haematoxylin from crude haematoxylin water extract which comprises treating the crude extract with a water immiscible organic solvent for haematoxylin, separating the water containing the impurities in solution, extracting the organic solvent with water to redissolve the haematoxylin in water, and separating and recovering the organic solvent.

15. The method of separating substantially pure haematoxylin from crude haematoxylin water extract which comprises treating the crude extract with an organic solvent for haematoxylin from the class including normal and secondary butyl alcohols, methyl ethyl ketone, furfural and tertiary amyl alcohol, separating the water containing the impurities in solution, extracting the organic solvent with water to redissolve the haematoxylin in water, and separating and recovering the organic solvent.

RAYMOND L. DREW.
